DISPLAY DEVICE

Melvin R. Greiser, Cincinnati, Ohio, assignor to
 Carthage Mills Incorporated, Carthage, Ohio,
 a corporation of Ohio

Application May 28, 1940, Serial No. 337,672

8 Claims. (Cl. 35—53)

This invention relates to a display device and more particularly to a device adapted for the selection of appropriate floor coverings for a given decorative scheme of the walls, ceilings and the like of a room. The selection of appropriate floor coverings in the decoration of a home is a difficult problem for the reason that it is almost impossible to get an adequate picture of what the complete room will look like from a small sample of floor covering material. It is impracticable to take a number of carpets out and try them in a room and it is not practicable to take samples of wall papers and the like to an establishment where floor coverings are sold for the purpose of determining the color harmony.

It is therefore an object of my invention to provide means whereby a color harmony for a decorative scheme for a room may be examined and judged without the necessity of moving large and cumbersome pieces of floor covering material out to the place where they are to be used.

It is a further object of my invention to provide a compact and readily portable arrangement whereby different decorative schemes of walls, ceilings and the like may be simulated, and whereby selectively different floor coverings may be shown in their relation to such a simulated room.

These and other objects of my invention which will be pointed out in more detail hereinafter or which will be apparent to one skilled in the art upon reading these specifications, I accomplish by that certain construction and arrangement of parts, of which I shall now describe exemplary embodiments.

Reference is now had to the drawings forming a part hereof and in which:

Figure 1 is a front elevation of one form of display device according to my invention.

Fig. 2 is a cross sectional view of the same taken on the line 2—2 of Fig. 1.

Fig. 3 is a cross sectional view on an enlarged scale taken on the line 3—3 of Fig. 2.

Fig. 4 is a cross sectional view taken on the line 4—4 of Fig. 3.

Fig. 5 is a perspective view of a modification of my display device.

Fig. 6 is a perspective view of a device similar to Fig. 5 but modified in part.

Fig. 7 is a perspective view with parts broken away to show the inner construction of a third modification of my device.

Briefly, in the practice of my invention, I provide means for simulating the walls and the ceiling, and the uncovered portion of the floor of a room. In connection therewith I provide also means for projecting onto the floor an image of a floor covering. In all the modifications shown herein the floor covering is provided by a projected image. In the embodiment of Figs. 1 to 4, the remaining parts of the room are also

formed by a projected image, while in Figs. 5 to 7 the decorative scheme of the walls is provided by inserts of appropriate design.

Referring more particularly now to Figs. 1 to 4 inclusive, I have shown at 10 in Fig. 1 a frame containing a screen of ground glass or the like 11. The frame is provided with a light shade 12 which may be omitted if desired. Fastened to the frame is a box-like element 13 (Fig. 2) which is preferably light tight and which may be provided with a door 14 if desired. At the end of the member 13 I mount a pair of projectors indicated generally at 15, each containing a projection source of light 16 and a continuous lens system generally indicated at 17. Each of the projectors contains a film transport arrangement indicated generally at 18 in Fig. 2, and each includes a lens system 19. As shown in Figs. 3 and 4, spools 20 are provided between which a roll of film 21 is transported. The film is transported by actuating the knobs 22 in the appropriate direction. The film transport per se forms no part of my invention and has been shown in a more or less diagrammatic way. Each film 21 passes over a mask device which serves as a film track and is generally indicated in the figures at 23 and 24. The masks 23 and 24 are generally similar except as to the opening therein. It will be noted from Fig. 3 that the mask 23 is provided with a generally rectangular opening 23a which is dimensioned by a generally trapezoidal portion 23. While the mask 24 has on the trapezoid an opening 24a.

It will now be clear that if a film having images of various arrangements is caused to travel past the mask 23 there will be projected upon the screen 11 the image of a room complete except for the floor. Now if a film is passed through the mask 24, which film bears images of different floor coverings, the images of these floor coverings will be projected into the space marked by the portion 23b of the portion 23. It is contemplated that colored film will be employed such as, for example, Kodachrome manufactured by the Eastman Kodak Company.

It will now be clear that one may first project through the mask 23 a film of various room arrangements and select one which corresponds most nearly to the type of room for which it is desired to provide a floor covering. Having selected a suitable room decorative scheme, it is now possible to project through the mask 24 selectively a variety of floor coverings. It will now be easy to select a floor covering which harmonizes with the general scheme of the room.

Referring now to Figs. 5, 6 and 7, I have shown modifications in which the floor covering only is displayed by means of a projected image and where the wall for this is produced by paper or cardboard either in the form of a roll having

sections with different panels or in the form of cardboard or the like inserts and in which the floor covering image may be projected from above as in Figs. 5 and 6 or from below as in Fig. 7. Referring specifically to Fig. 5 I have shown a box having a top 25 and a bottom 26. This box has front corner posts 27 and rear corner rods 28. Adjacent the corner posts 27 I mount rollers 29 in brackets 30. The rollers are provided with cranks 31. Passing from one roller 29 through a slot 32 in the corner post 27 and behind the rods 28, and again through the slot 32 in the other corner post 27, and onto the second drum 29 is a strip of paper or the like indicated generally at 33, carrying wall paper designs. I contemplate that successive lengths of the material 33 equal to the combined length at least of the three walls of the box 25 shall have different designs.

In order to give the effect of windows, doors or the like, I mount over the wall spaces sheets of transparent material such as Cellophane, indicated generally at 34, bearing representations of the window or the like indicated generally at 35. The areas of such a window which would be glass, as indicated at 36, are made of an opaque material so that the wall paper design will not show through. For the purpose of illuminating the walls I provide lamps indicated generally at 37 provided respectively with shields 38, whereby they will not illuminate the floor 26.

Mounted on the top 25 of the box is a projector indicated generally at 39 which may be of any desired type, and images of floor covering materials in the form of a glass slide indicated generally at 40 may be passed through the projector to form an image 40 of the rug or the like.

In Fig. 6 the wall portions are formed by pieces of card board and the like, indicated generally at 41, which may be slid into place through slots 42 in the top. Also in Fig. 6 I have shown a film carriage 43 rather than the slide arrangement of Fig. 5 although it will be understood that either of these arrangements may be used in any of the embodiments herein described.

In Fig. 7 I have shown another modification in which the projection apparatus is housed in a casing 44. The top of the casing 44 represents the floor of a room and the walls may be represented by forms 46 of various designs. In the top of the casing 44 is a projection screen of ground glass or the like, indicated at 47 to receive the image of the floor covering material. Within the casing I have indicated generally at 48 a projector and at 49 an endless strip of film passing through the focal plane of the projector and carried about an arrangement of rollers 50. A sprocket 51 is provided for advancing the film, and the sprocket is actuated by means of a ratchet mechanism indicated generally at 52 by means of the arm 53. The arm 53 is urged upwardly by means of a spring 54 and is operated by means of a solenoid 55 working against the spring 54. The solenoid 55 may be actuated by a push button 56 on the outside of the casing and appropriately connected electrically with a source of power and the solenoid. Such electrical connections form no part of my invention and will therefore not be described in detail.

With the arrangement of Fig. 7 an appropriate wall arrangement is set up at 46 and then the push button 56 is actuated, bringing successively a large number of images of floor coverings onto the screen 47 for comparison with the wall members 46.

While I have described several modifications of my invention, it will be clear that numerous other modifications will suggest themselves to one skilled in the art, and such modifications may be made in my invention without departing from the spirit thereof. I therefore do not intend to limit myself except as pointed out in the claims which follow, and as the prior art requires.

I claim:

10. 1. A device of the class described comprising a box open at one side at least, means for displaying in the remaining three sides a representation of wall paper, and means for selectively projecting onto the bottom of said box an image of a floor covering.
15. 2. A device of the class described comprising a box open at one side at least, rotatable drums mounted adjacent said opening on opposite sides thereof, means for conducting a strip of paper or the like from one drum to the other over the three remaining sides of said box, said strip of paper or the like carrying representations of various kinds of wall paper, and means for projecting onto the bottom of said box selectively an image of a floor covering.
20. 3. A device of the class described comprising a box open at one side at least, rotatable drums mounted adjacent said opening on opposite sides thereof, means for conducting a strip of paper or the like from one drum to the other over the three remaining sides of said box, said strip of paper or the like carrying representations of various kinds of wall paper, means for projecting onto the bottom of said box selectively an image of a floor covering, and means for independently illuminating the walls of said box while shielding the bottom thereof.
25. 4. A device of the class described comprising a box open at one side at least, rotatable drums mounted adjacent said opening on opposite sides thereof, means for conducting a strip of paper or the like from one drum to the other over the three remaining sides of said box, said strip of paper or the like carrying representations of various kinds of wall paper, means for projecting onto the bottom of said box selectively an image of a floor covering, and means for independently illuminating the walls of said box while shielding the bottom thereof.
30. 5. In a device according to claim 2 a transparent material bearing an opaque representation of a wall opening and trim, extending over a wall in front of said strip of paper.
35. 6. A device according to claim 1 in which the means for displaying representations of wall paper comprise inserts of relatively stiff material selectively disposed against said remaining walls.
40. 7. A device of the class described comprising a casing, a projection screen in the top of said casing, means for displaying about said screen representations of various kinds of wall paper, and projection means within said casing for selectively projecting an image of a floor covering material onto said screen.
45. 8. A device according to claim 7 in which said projection means comprises a projector, an endless strip of film, means for feeding said film through said projector, solenoid means for actuating said feeding means, a push button on the outside of said casing and an operative circuit including said push button and said solenoid.

MELVIN R. GREISER.
